United States Patent Office.

JOHN JOSEPH CHARLES SMITH, OF SOMERVILLE, ASSIGNOR TO THE METALLIC COMPRESSION CASTING COMPANY, OF BOSTON, MASSACHUSETTS, ASSIGNOR TO RUSSELL & ERWIN MANUFACTURING COMPANY, OF NEW BRITAIN, CONNECTICUT.

Design No. 4,129, dated June 7, 1870.

DESIGN FOR A BELL-PULL KNOB.

The Schedule referred to in these Letters Patent and making part of the same.

I, JOHN JOSEPH CHARLES SMITH, of Somerville, in the county of Middlesex and State of Massachusetts, have invented and produced a new original design for a Bell-pull Knob, of which the following is a specification.

The nature of my design is represented in the accompanying photographic illustration, to which reference is made.

I claim the design for a bell-pull knob, substantially as above set forth.

JOHN JOSEPH CHARLES SMITH.
